UNITED STATES PATENT OFFICE.

ERNST WÖLFER, OF GOTHA, GERMANY.

CAN-OPENER.

1,024,543.

Specification of Letters Patent.

Patented Apr. 30, 1912.

Application filed April 29, 1911. Serial No. 624,076.

To all whom it may concern:

Be it known that I, ERNST WÖLFER, a subject of the German Emperor, residing at Gotha, in Germany, have invented certain new and useful Improvements in Can-Openers, of which the following is a specification.

In can-openers hitherto used with cutters, the opening of the can is effected by the 10 opener being stuck into the cover of the can whereupon the can is cut in slow strokes. The surface of the cut is always jagged and therefore it is very easy to injure the hands when taking out the conserve contained in 15 the can. Moreover, the work of opening the can is very difficult, as the sticking in of the opener and the cutting of the can by the same, requires the use of considerable force.

By means of the device forming the subject of this invention, leverage is utilized in combination with suitable cutting tools, whereby the cutting out of the can cover is rendered very easy.

The can opener is shown in the accompanying drawing, in which—

Figure 1 is a side elevation and Figs. 2 and 3 illustrate diagrammatically the methods of using the opener.

As a cutting tool a rotary cutter *a* driven 30 by means of a crank or lever *b* provided with a handle, is used in place of the usual stationary cutter. The essential novelty of the construction according to this invention is that the rotary cutter *a* is mounted in an 35 easily adjustable manner on one branch *c* of a pair of tongs. The rotary cutter *a* is made of any desired size and provided on the back with a friction wheel *d* secured to the cutter. When the crank *b* is oscillated, the parts *a* and *d* mounted on the 40 same spindle also oscillate. On the opposite side, that is to say, on the other branch of the tongs, is mounted a friction wheel *e* in such a manner that, when the branches of 45 the tongs are closed, the wheel *e* engages with the friction wheel *d*. The opening and closing of the tongs is effected by the branches *f* in the known manner. The part 50 of the tongs, on which the rotary cutter *a* is mounted, is extended outward into a bracket *g* carrying a stationary cutter *h*, and lateral protective ledges *i* are used for inclosing at the sides the driving gear *a d e*, in order to prevent injury during the 55 rotation.

The working of the can opener is as fol-

lows: By opening the branches *f* of the tongs, the friction wheel *e* is moved away from the rotating cutter *a* and the friction wheel *d*. Into the opening thus produced 60 is introduced the edge of the can which is to be opened, so that the edge of the can, which is produced by the pressing on of the cover, lies in the middle. When the branches *f* of the tongs are pressed together, 65 the friction wheel *e* lies on one side of the edge of the can, and on the other side the cutter *a* engages with the can. If a slight pressure is exercised on the branches *f*, the cutter *a* will cut the can at the point of 70 contact, and to such a depth that the friction wheel *d* firmly adjoins the sheet metal wall with which the friction wheel *e* engages on the other side. If the tongs are held closed, and the crank *b* further rotated, 75 the friction wheel *d* will bring about the advance of the whole tool, while the friction wheel *e* acts as a guide on the opposite side. During this further movement, the rotary cutter *a* smoothly cuts out the cover in a complete circle. The can so opened can be used 80 again after suitably flanging over the upper edge, as no bends of any kind are formed in cutting. If it is desired to cut a thick part of the can for instance the soldered part, or 85 the like, or if the bending upward of a flanged over portion becomes necessary, this is effected by means of the cutter *h*, and one half of the tongs is then used as an abutment against which the cutter *h* cuts 90 (Fig. 3).

The can opener can be manufactured in a simple manner and is highly practical owing to its combination of leverage with cutting tools. All the movable parts, more 95 particularly the cutter *a* and the friction rollers, can be made easily interchangeable, and in place of one branch of the tongs a fixed bottom bracket can be used which for instance could be screwed to a table. 100

What I claim as my invention and desire to secure by Letters Patent is:—

1. In a can opener the combination of a pair of tongs, a circular cutter and a conical friction wheel rigidly connected thereto 105 mounted on one arm of the tongs, crank mechanism adapted to rotate the cutter, and a second friction wheel mounted on the other arm of the tongs and adapted to engage the first cutter for the purpose set 110 forth.

2. A can opener comprising a pair of

- tongs, a cutter rotatably mounted on one branch of the tongs, a lever rigidly connected to said cutter, a friction wheel on the branch which carries the cutter, and a 5 second friction wheel mounted on the other branch of the tongs for the purpose set forth.
3. A can opener comprising a pair of tongs, a cutter rotatably mounted on one 10 branch of the tongs, a lever rigidly connected to said cutter, a friction wheel secured to the cutter, and a second friction wheel mounted on the other branch of the tongs for the purpose set forth.
- 15 4. A can opener comprising a pair of tongs, a cutter rotatably mounted on one branch of the tongs, a lever rigidly connected to said cutter, a friction wheel secured to the cutter, a second friction wheel 20 mounted on the other branch of the tongs,

and a protective ledge for the cutter and friction wheels for the purpose set forth.

5. A can opener comprising a pair of tongs, a cutter rotatably mounted on one branch of the tongs, a lever rigidly connected to said cutter, a friction wheel secured to the cutter, a second friction wheel 25 mounted on the other branch of the tongs, a protective ledge for the cutter and friction wheels, and a fixed cutter secured to a 30 bracket on one branch of the tongs for the purpose set forth.

In testimony whereof I have signed my name to this specification in the presence of two subscribing witnesses.

ERNST WÖLFER.
